UNITED STATES PATENT OFFICE

WELLS S. FLEMING, OF PORTLAND, OREGON

DRAIN FIXTURE

Application filed November 28, 1928. Serial No. 322,448.

My invention relates to drain fixtures especially adapted for roofs of the so called "saw-tooth" design.

The saw-tooth roof design, as well known, 5 comprises parallel sections, vertical on one side and sloping on the other, in order to obtain increased roofing area and provide vertical glassed in surfaces arranged to receive the direct rays of the sun and thus obtain a 10 maximum of sunlight and ventilation for a given amount of floor space.

In such construction the problem of economically and efficiently draining the valleys between the saw-tooth sections arises.

15 In this connection it is to be noted that while many of the roofs are built to give the saw-tooth sections a 30 degree angle of slope, it is sometimes desirable to construct the sections on a steeper or flatter angle, thus requiring especially made drain fixtures to fit the 20 given angle, which at the same time, must drain the moisture from the bottom of each valley, so that no pools of water will collect to the damage of the roof.

25 Therefore the object of my invention is to provide a simple and economical drain fixture adaptable for draining the valleys of a saw-tooth roof of any given angle of slope without alteration or adjustment and capable of 30 being connected to the usual arrangement of drain pipes regardless of the angular arrangement of the drain fixtures and the slope of the saw-tooth sections.

Another object of my invention is to provide 35 a drain fixture of this character, adapted to lie flush in the bottom of the valley between the saw-tooth sections, so that no moisture will collect therein in pools on the roofing material with which the roof is covered.

40 A further object of my invention is to provide a drain fixture adapted to effect a moisture proof seal at its rim with the water proofing membrane of the roof.

To this end I provide a drain fixture comprising 45 a basin-body having opposite sides making an acute angle with each other, one side being of greater height than the other, the basin-body open at the top and the plane touched by the rim thereof making an acute angle with the higher of the said sides, the

end walls of the basin adapted to have drain pipes connected thereto so that by rotating the basin-body about its longitudinal axis extending through the said end walls, the rim of the basin-body may be adjusted to any 55 angle of slope of a saw-tooth section, without alteration, or changing the alinement of the drain fixture with the drain pipes of the building.

These and other incidental features of my 60 invention, the objects thereof, the details of construction, and the mode of installation will be hereinafter fully described with reference to the accompanying drawings.

In the drawings:

Fig. 1 shows a plan view of my drain fixture and illustrates fragmentary portions of the roofing membrane clamped in place;

Fig. 2 shows a section taken on the line 2—2 of Fig. 1;

Fig. 3 shows a section taken on the line 3—3 of Fig. 2;

Fig. 4 shows diagrammatically, the relative arrangement of my drain fixtures in the valleys of a saw-tooth roof;

Fig. 5 shows a section taken on the line 5—5 of Fig. 4, and illustrates the arrangement of my drain fixtures within a valley; and

Fig. 6 shows a fragmentary side view of a saw-tooth section constructed with a steeper 80 angle of slope than in Fig. 4, and illustrates how my drain fixtures are installed without alteration to the construction of the building.

With reference to the figures, my drain fixture comprises a basin-body *a* provided with 85 a cylindrical cavity *b* in its bottom, which is open at the ends and threaded as at *b'* to receive suitable drain connections.

The side walls *c*, *d* of the body member *a* form an acute angle with each other, and the 90 side wall *d* is of lesser height than the side wall *c* and is a plane surface, the side wall *c* being curved to meet the plane surface of the wall *d*, thus forming in a plan view an oval with one straight side formed by the wall *d*, 95 as shown in Fig. 1.

The plane of the rim of the basin-body *a* forms an acute angle with the higher side *c* of the basin-body to conform to the angle of slope of the saw-tooth section to which it is 100

attached, and is provided with an outwardly and upwardly flaring flange *e*.

Rest lugs f and sockets g are formed in the interior of the basin-body adjacent the rim which respectively supports and forms a hinged connection for a grille plate h , which lies in a plane parallel to the said plane of the rim.

10 A clamping ring *i* is provided adapted to be seated on the flange *e* and to have a roofing membrane *2* clamped between. The ring *i* is provided with threaded sockets *j* arranged to register with companion threaded sockets *k* in the flange and to receive bolts *l*, by
15 which the clamping ring is closely secured to the said flange.

The axis of the sockets j and k are parallel, so that the clamping strain of the bolts will all be in the same direction and will not tend to disrupt the clamping ring or flange when tightly threaded into place.

Suitable means, such as exterior lugs *m* are provided about the basin-body for supporting the drainage fixture on the roof structure 3.

As illustrated in Figs. 4 and 5, my drainage fixture is adaptable to saw-tooth sections of any angle by merely rotating the fixture on the longitudinal axis of the cylindrical cavity b ; in other words by merely placing the fixture in the cut-out port on prepared in the roof structure to receive the drain fixture, the center line or axis of the cavity b will lie in the same straight line and the alignment of the connecting drain pipe n with other drains in the same valley will not be disturbed as shown in Figs. 5 and 6.

To further illustrate how my drain fixture is thus adjustable to saw-tooth roof sections of varying degrees of slope, in Fig. 4, is shown my drain fixture installed in the saw-tooth roofs of 30 degrees slope, and in Fig. 6, I have shown diagrammatically a similar fixture installed on a 45 degree slope.

45 Figs. 2 and 4 also illustrate how my drain fixture is arranged to lie flush in the bottom of the valley so as to efficiently drain the same and form a moisture proof seal with the roofing membrane. In the form of roof construction 50 illustrated here, a layer of plastic material 4 has been laid over the roof structure and the flange *e* is laid flush in the said plastic material, so that the roofing membrane 2 as arranged between the flange *e* 55 and the clamping ring *i*, is slightly above the level of the plane of the rim of the drain fixture, and since the clamping ring *i* is contained flush within the flange *e*, no moisture will collect about the drain, but will tend to 60 run into it and be carried off.

I claim:

A drain fixture comprising a basin-body having opposite sides making an acute angle with each other, one side being of greater height than the other, the interior face of the

side of lesser height being substantially plane and the side of greater height being formed to meet said plane face, the basin-body being open at the top and the plane touched by the rim thereof making an acute angle with the higher of said sides, one end wall of the basin-body being adapted to have a drain pipe connected thereto, and a clamping ring removably secured on the rim of said basin-body to secure the margin of a sheet of roofing material. 70 75
